(57) **CLAIM**

The ornamental design for an adjustable anti-snoring mouthpiece, as shown and described.

DESCRIPTION

FIG. 1 is a perspective view of an adjustable anti-snoring mouthpiece in an open position, showing the new design; FIG. 2 is a perspective view of the adjustable anti-snoring mouthpiece in a closed position;

FIG. 3 is another perspective view of the adjustable anti-snoring mouthpiece in an open position;

FIG. 4 is a front elevation view thereof;

FIG. 5 is a back elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines shown in the figures depict portions of the adjustable anti-snoring mouthpiece that form no part of the claimed design.
